UNITED STATES PATENT OFFICE.

ANDRÉ VALLAT, OF PARIS, FRANCE, ASSIGNOR TO M. SOL LESSER, OF LOS ANGELES, CALIFORNIA.

CABIN FOR LIGHT-PRODUCING DEVICES.

Application filed December 16, 1926, Serial No. 155,250, and in France April 20, 1926.

My invention has for its object a cabin inside which the device producing the light necessary chiefly for photographic purposes is produced either through igniting flash powder such as magnesium powder, or through any other means. The essential feature of this cabin resides in its trapezoidal shape, the longer side facing the part which it is desired to illuminate whereby the light produced is reflected by the three other sides so as to converge in the desired direction and to provide the maximum illumination of the object to be photographed.

When the source of light is flash-powder, the cabin is entirely closed so as to avoid any dust from being projected after ignition. In this case all the sides are of opaque material such as metal except the long front side which is transparent and made of fire-proof canvas.

The ignition of the powder can be produced by any suitable device; my invention relates in particular to a very simple and convenient form of execution of such a device. My improved cabin can be executed either for workshop purposes in which case it is stationary or for booth purposes and the like in which case it is portable. In this latter case the whole casing may be made of fire-proof canvas, the front side remaining alone transparent; this canvas cabin is preferably made up like a pair of bellows and is hung so as to blow away the smoke through suitable apertures after each ignition through the action of these bellows. I have shown two forms of execution of my invention on appended drawings by way of example:

Fig. 1 is a perspective view of the workshop cabin taken towards the front.

Fig. 2 is a similar view taken towards the rear.

Fig. 3 is a horizontal section of the same cabin.

Fig. 4 is an inner view of the safety door used with this cabin when flash-powders are used for illuminating purposes.

Fig. 5 is a perspective view of the said door with its circuit breaking device.

Fig. 6 is a diagram of the electric connections of this apparatus.

Fig. 7 is a perspective view of the portable bellows-shaped apparatus.

Fig. 8 is a plan view from below of the same apparatus.

In the form of execution shown on Figs. 1 to 6, the cabin comprises a frame 1 preferably of metal and having a trapezoidal shape. All the sides reflect the light emitted by the luminous source except the transparent front side 2 which is preferably closed like the other sides especially if the luminous source is constituted by flash powder such as magnesium.

In this latter case the rear wall 3 bears a suitable number of apertures 4 adapted to be closed each by a double pivoting shutter one of the leaves 5 of which is outside the wall 3 and the other 5' is inside the said wall. The two leaves are secured to each other by a small plate 6 bearing the magnesium burner or burners 7.

These burners are connected through wires 8 to contact pieces 9 borne by the inner leaf 5' of the shutter. These contact pieces come, when the shutter closes the aperture 4, against the contact parts 10 secured to the inside of one of the lateral walls of the cabin 1. These contact parts are connected with the terminals of an electric circuit comprising a supply 11 and a switch 12 common to all the circuits corresponding to the several burners (Fig. 6).

Evidently when the shutter 5—5' closes the aperture the contact pieces 9 come against the contacts 10 and if the general switch 12 is closed, the current will flow through 10, 9 and 7 and thence back to the supply by any suitable means. For instance, as shown, each burner may be double and the current may return by means of a spark through the second contact 9—10 borne as shown by the shutter. Thus the burners 7 will be ignited. The light intensity produced can be adjusted by adjusting the number of burners used, each of these being provided with its own switch.

When the shutter does not close the aperture 4, no contact is produced between parts 9 and 10 whereby early ignition is prevented.

Of course, as stated hereinbefore, the igniting device can be executed in any suitable manner besides that which has been described.

The portable cabin shown on Figs. 7 and 8 has also trapezoidal cross-section (Fig. 8). All the walls thereof are of fireproof canvas and act as a pair of bellows. The arrangement is suitably hung up and only the front wall is translucent. The bottom shows in its

center a circular hole 14 adapted to be closed by a plug 15 bearing the magnesium burner. It can be removed from outside through a handle not shown projecting outside the cabin and is provided with an outlet hole 17 similar to the hole 18 provided in the cover 19 of the cabin.

What I claim is:

1. A cabin for the production of light for photographic purposes comprising a closed upright casing having a trapezoidal section, the front wall of which is transparent and the rear wall of which is provided with holes, shutters pivotally secured to the rear wall of the casing and each adapted to close a corresponding hole in the said wall, said shutters each consisting of two vertical leaves secured together along the pivoting axis of the shutter and disposed respectively inside and outside the casing and a horizontal plate connecting the two leaves together, burners borne by the plate of each shutter and means for igniting said burners.

2. In a cabin as claimed in claim 1, contact pieces borne by the inner leaf of each shutter and electrically connected with the corresponding burner, contact parts disposed inside the casing and adapted to bear against the said contact pieces in their inner position, an electric supply, electric circuits connecting the supply with the burners and a switch common to said circuits.

3. In a cabin as claimed in claim 1, contact pieces borne by the inner leaf of each shutter and electrically connected with the corresponding burner, contact parts disposed inside the casing and adapted to bear against the said contact pieces in their inner position, an electric supply, electric circuits connecting the supply with the burners, a switch for each circuit, and a switch common to said circuits.

In testimony whereof I have affixed my signature.

ANDRÈ VALLAT.
